A. Schapp
ATTORNEY

door, the operator places the bar 1 against the side of the door adjacent the edge, with the flange 2 projecting across the door edge, and with the blades 4 facing the edge in position for cutting the mortise.

The jig is secured in proper position with respect to the door edge by adjustment of the members 8 to cause the latter to bear on the side of the door opposite the bar 1.

During this positioning of the jig with respect to the door, the blade 5 is held in retracted position by proper positioning of the handle 6.

Next the operator strikes the insert 13 with a hammer to cause the blades 14 to penetrate the edge of the door to the depth of the desired mortise, and thereupon he swings the handle 6 toward the bar 1 to cause the blade 5 to enter the door edge from the side and to cut the bottom of the mortise. This completes the operation.

It is apparent that the stops or holding members 8 do not need to be adjusted for each operation, but may be used in the same position as long as the doors to be mortised have the same thickness. On the other hand, they can be adjusted for doors of different thicknesses, and the width of the flange is such that it allows the stop members 8 to be easily adjusted for use in connection with a door jamb or the like.

The blade 5 may have a comparatively narrow and smooth sliding fit in the bar 1, since the link connection 15 has sufficient give to prevent any binding of the blade within the bar.

I claim:

1. A jig for mortising a door edge or the like comprising a bar having an inner edge adapted for placing against the side of the door, a flat flange projecting from the inner edge of the bar across the door edge and adapted to lie flat against the latter and made to project beyond the door edge, means on the projecting portion of the flange for bearing on the opposite side of the door edge, the flange having fixed blades projecting toward the door edge to define a rectangular mortise area adjacent the bar and to cut the edges of the mortise when hammered into the door, a bottom cutting blade retractable in the bar in the plane of the extremi-

ties of the edge cutting blades, and means for driving the bottom cutting blade into the door for cutting the bottom of the mortise, the latter means comprising a straight handle disposed upon the outer edge of the bar and normally lying adjacent thereto, a link connection between corresponding ends of the handle and the bar, and a pivotal connection between the handle and the bottom cutting blade.

- 10 2. A jig for mortising a door edge or the like comprising a bar having an inner edge adapted for placing against the side of the door, a flat flange projecting from the inner edge of the bar across the door edge and adapted to lie flat against the latter and made to project beyond the door edge, means on the projecting portion of the flange for bearing on the opposite side of the door edge, the flange having fixed blades projecting toward the door edge to define a rectangular mortise area adjacent the bar and to cut the edges of the mortise when hammered into the door, a bottom cutting blade retractable in the bar in the plane of the extremities of the edge cutting blades, and means for driving the bottom cutting blade into the door for cutting the bottom of the mortise, the latter means comprising a straight handle disposed upon the outer edge of the bar and normally lying adjacent thereto, a link connection between corresponding ends of the handle and the bar, and a pivotal connection between the handle and the bottom cutting blade, and the free end of the handle projecting beyond the corresponding end of the bar to facilitate the operation of the handle.

TANNER H. BROWN.
